UNITED STATES PATENT OFFICE.

LESTER R. ARNOLD, OF WORCESTER, MASSACHUSETTS, ASSIGNOR, BY MESNE ASSIGNMENTS, TO EDWARD C. BOWERS AND CHARLES L. FELDMAN, RECEIVERS.

CARD CLOTHING.

Application filed July 21, 1926. Serial No. 124,076.

This invention relates to the manufacture of card clothing such as is used on the rolls of carding engines or for other similar purposes.

5 It is the general object of my invention to provide means for causing the card clothing to lie more smoothly against the roll or cylinder and to be more firmly retained in position thereon.

10 A further object is to increase the strength and durability of the card clothing.

To the attainment of these objects, I provide a facing layer of thin sheet steel or other suitable material, covering the outer 15 face of the body portion or backing of the card clothing. The use of such a facing layer possesses important advantages which will be hereinafter described and more fully pointed out in the appended claims.

20 A preferred form of the invention is shown in the drawings in which

Fig. 1 is a side elevation of a portion of card clothing embodying my invention;

Fig. 2 is a plan view of the reinforcing 25 strip of metal facing;

Fig. 3 is a side elevation of a modification; and

30 Figs. 4 and 5 are enlarged detail sectional views of the structure shown in Figs. 1 and 3 respectively.

Referring to the drawings, my improved 35 card clothing comprises a body portion or backing 10 which may be of leather or of a suitable woven material such as is commonly used in the manufacture of card clothing.

A facing member or covering strip 12 is 40 placed against the outer face of the body member 10 and the U-shaped pins 14 are inserted through aligned perforations in the body 10 and in the facing strip 12.

The facing strip 12 may be formed of 45 different kinds of thin sheet material such as copper, zinc or tin, but I have found that very satisfactory results are attained by the use of a sheet of very thin sheet steel, preferably not over four or five thousandths of an inch in thickness.

Steel of this thickness may be readily 50 perforated by the needles which perforate the backing or body portion prior to the insertion of the pin wires, and at the same time it possesses strength and resilience to an extent sufficient for the purpose intended.

In the manufacture of my improved card

clothing, the facing strip 12 is fed through 55 the machine with the backing 10, and both layers are simultaneously perforated and the wires are inserted therein practically as a single operation.

The needles which make the perforations 60 are somewhat larger than the pin wire, so that the pins fit rather loosely in the openings through the metal facing. This is of importance, as it permits a certain yielding movement of the pins and does away with 65 the tendency of the pins to break off at the point where they pass through the metal plate.

This thin sheet steel facing also possesses 70 considerable resilience and causes the card clothing to hug tightly against the drum or cylinder on which it is wound, preventing buckling of the card clothing and causing it to retain the accurate cylindrical form required for carding operations.

75 The metal facing also increases the tensile strength of the card clothing and permits it to be wound on the cylinder under greater tension, thus securing a tighter fit of the clothing against the cylinder.

80 In Fig. 3 I have shown a modified construction in which the layer of sheet material is applied at the back rather than on the face of the body portion. While this construction lacks certain of the advantages 85 of the preferred form, it substantially increases the strength of the card clothing and permits the same to be wound on the cylinder under a greater tension than has been heretofore used.

90 Having thus described my invention and the advantages thereof, I do not wish to be limited to the details herein disclosed otherwise than as set forth in the claims, but what I claim is:

1. Card clothing comprising a relatively soft pin-retaining body portion, a thin flexible layer of resilient sheet material forming a facing for said body portion, and a plurality of pins extending tightly through 100 said body portion and loosely through perforations in said facing layer.

2. Card clothing comprising a relatively soft pin-retaining body portion, a thin flexible stiffening layer of resilient sheet material forming a facing for said body portion, and a plurality of pins extending through 105 aligned perforations in said body portion

and said facing layer, said facing layer having perforations therein for said pins which are of slightly larger diameter than the pins.

3. Card clothing comprising a body portion, a thin layer of sheet steel forming a facing for said body portion, and a plurality of U-shaped pins extending through

aligned perforations in said body portion and said steel facing layer and loosely fitting the perforations in said facing layer. 10

In testimony whereof I have hereunto affixed my signature.

LESTER R. ARNOLD.
